UNITED STATES PATENT OFFICE.

KARL J. EKEDAHLL, OF CICERO, ILLINOIS.

TIRE-PROTECTOR.

1,356,702.

Specification of Letters Patent. Patented Oct. 26, 1920.

Application filed March 26, 1919. Serial No. 285,154.

To all whom it may concern:

Be it known that I, KARL J. EKEDAHLL, a subject of the King of Norway, residing at Cicero, in the county of Cook and State of Illinois, have invented certain new and useful Improvements in Tire-Protectors, of which the following is a specification.

This invention relates to improvements in tire protectors and more particularly to protectors for pneumatic tires whereby blow-outs and punctures are avoided. The invention contemplates an inner-liner designed to be inserted between the casing and inner tube and provided with a central band composed of a plurality of connected metal plates, inserts being provided between the corners of the plates, the band being held in position by laterally extending anchor-chains. The invention, more specifically, consists in the combination and arrangement of parts to be hereinafter fully described, pointed out in the appended claims and illustrated in the accompanying drawings which form a part of this specification and in which—

Figure 1 is a cross section through a pneumatic tire, upon a rim, provided with my improved protector.

Fig. 2 is an enlarged fragmentary view of the central band showing the face that is disposed against the insert fabric.

Fig. 3 is a fragmentary plan view of the device.

Fig. 4 is a perspective view of a modified form of anchor sometimes employed.

Fig. 5 is another form of anchor.

Fig. 6 is a section taken on line 6—6 of Fig. 5.

Fig. 7 is a perspective view of the insert employed between the corners of the band-plates.

Fig. 8 is another form of anchor that may be employed.

Fig. 9 is a section taken on line 9—9 of Fig. 8.

Like reference characters denote corresponding parts throughout the several views.

The reference numeral 1 denotes the felly, 2 the rim, 3 the tire casing and 4 the inner tube. My protector comprises the main strip of canvas 5 that is disposed between the casing and the inner tube and that receives the latter member direct, said strip being substantially co-extensive with the casing 3. Upon the main strip 5 the later-

ally disposed longitudinally extending strips 6 are arranged and sewed thereto as at 7 along one edge and by spaced stitches 8 along the opposite edge. Hooks 9, or 10, 60 or 11, or 12 are secured by plates 13, or 14, or 15, or 16 to the casing 3, the plates 15 being formed with the flexible fingers 17 and the plates 16 being identical with the plates 13 except being disposed at right angles 65 thereto to permit of longitudinal sliding engagement by the hooks 16. Minor advantages may be found in the use of one form of anchor over another, an anchor comprising one type of hook with its plate. Each 70 hook engages and supports a tie rod 18 to which the chains 19 are secured which chains engage with certain of the links 20 of the metal plates 21, said plates being connected together also by said links, said links 75 engaging directly with the bent lateral edges 22 of said plates. The plates 21 substantially four abreast extend entirely around the main strip 5 centrally of the same and are held in position by the chains 80 and connections described, said plates bearing directly upon the strip 5 and the inner surface of the casing 3 and preventing nails, tacks and the like from puncturing the inner tube.

The plates 21 are preferably square in shape and between the corners of the adjacent plates forming the band I provide inserts comprising the spaced disks 23, 24 connected by the pins 25, the ends of the links 90 20 connecting the adjacent plates 21 being disposed between the spaced disks to retain the insert in position, the purpose of the insert being to prevent punctures of the inner tube between the corners of the protecting plates.

What is claimed is:—

1. In a tire protector, a main strip co-extensive with the tire casing, lateral strips arranged upon said main strip and secured thereto, hooks connecting said main strip and lateral strips to the tire casing, tie rods carried by said hooks, connected plates extending longitudinally of said main strip, connection between said plates and the said tie rods, and inserts disposed between the corners of adjacent plates.

2. In a tire protector, a main strip co-extensive with the tire casing, lateral strips arranged upon said main strip and secured thereto, hooks connecting said main strip and lateral strips to the tire casing, tie rods

carried by said hooks, plates formed with bent lateral edges and disposed centrally of said main strip and extending longitudinally thereof, links connecting the bent edges of said plates to each other, spaced connected disks disposed between the adjacent corners of said plates and engaging said links, and chain connection between said links and said tie rods.

In testimony that I claim the foregoing 10 as my own I have hereto affixed my signature in the presence of two subscribing witnesses.

KARL J. EKEDAHL.
